UNITED STATES PATENT OFFICE.

CARL E. B. OSBERG, OF DES MOINES, IOWA, ASSIGNOR TO ROLLINS HOSIERY MILLS, OF DES MOINES, IOWA, A CORPORATION OF IOWA.

NEEDLE FOR REPAIRING RUNS IN KNITTED GOODS.

Application filed May 10, 1927. Serial No. 190,244.

The object of my invention is to provide a knitting needle of simple, durable and inexpensive construction, which is especially adapted for repairing runs in knitted goods, 5 so that the repairing of said runs may be more easily and quickly accomplished.

More specifically it is the object of my invention to provide in a needle of that type having a hook and a pivoted latch for closing the hook, simple and compact means whereby the latch will be automatically thrown from a closed position to an open position, after the latch has been released, 10 and to provide in connection therewith means whereby the latch will be frictionally retained in said open position.

My invention consists in the construction, arrangement and combination of the various parts of my device, whereby the objects contemplated are attained, as hereinafter more 20 fully set forth, pointed out in my claims, and illustrated in the accompanying drawings, in which:

Figure 1 is a side elevation of my improved 25 knitting needle with the latch member moved to its open position.

Figure 2 is a sectional view of the lower 30 end of said needle with the latch in its closed position.

Figure 3 is a detail sectional view taken 35 on the line 3—3 of Figure 2.

Figure 4 is a detail sectional view taken 40 on the line 4—4 of Figure 1.

Figure 5 is a sectional view of a slightly 45 modified form of my needle.

Figure 6 is a detail sectional view taken 50 on the line 6—6 of Figure 5.

My improved needle comprises a body portion 10, one end of which is provided with a 55 suitable handle 11 and its opposite end provided with a hook portion 12. The body 10 has a central slot 13 which extends between its back and front edges, the front edge of the slot being wider than the back edge. A latch 14 is provided for closing the entrance to the hook 12. One end of the latch is flattened and pivotally mounted within the slot 13 by means of a pivot 15. The free end of the latch 14 is provided with a widened portion 16 for covering the free end of the hook 12. The inner end of the hook portion 12 is provided with a notch 17 designed to receive one end of a short spring 18, the other end of said 60 spring being designed to extend toward the pivot 15 and adapted to engage the inner 65 providing means for frictionally retaining 70

edge of the latch 14 at the time the latch 14 is nearly moved to a closed position, so that as the free end of the latch is moved to a closed position, the free end of the spring 18 will be bent rearwardly and place yieldable 60 tension on the latch, so that when the free end of the latch is released, it will be thrown from the closed position shown in Figure 2, to the open position shown by dotted lines in Figure 2. It will be seen that the outer edge 65 of the body of the latch 14 will pass into the upper end of the groove 13 and between the side members 19 of the body 10.

In order to frictionally retain the latch in an open position, I have curved the outer 70 edges of the side members 19 slightly and crimped them inwardly as shown at 20 in Figures 3 and 4, so that the said crimped or bent portions will frictionally engage the member 14, it being understood that the side 75 members 19 are very thin in the actual needle and slightly yieldable.

In the operation of the needle, the hook 12 is placed through the loop 21 of the knitted goods 22 and moved downwardly until the 80 upper end of the latch 14 rests below the forward end of said loop, after which the needle is elevated, causing the latch 14 to be swung downwardly and the hook 12 to engage a new thread 23. This upward movement is continued until the loop 21 passes over the free end of the latch 14, at which time tension is applied to the spring 18. After the loop is passed over and released from the latch, the spring will be thrown into its elevated position with sufficient force to cause the member 14 to enter frictionally between the members 20. The thread 23 is then pulled upwardly 85 through the loop 21 thereby forming a new loop, after which the above operation may be 90 repeated.

In Figure 5 I have shown a slightly modified form in which the inner end of the groove 13 is filled with an elastic material 24, such as rubber or cork, in such a manner that the 100 outer edge of the elastic material will be engaged by the inner edge of the latch 14, just before it is moved to its closed position. The resiliency of said material is sufficient to pull the latch to its open position in the manner 105 similar to that of the spring, although I find by actual practice that the spring is preferable.

One of the advantages of my device lies in 110 providing means for frictionally retaining

the latch in its open position, as this will retain the latch in its elevated position as the hook 12 is being moved downwardly between the parallel strands of the run. If the latch 5 were not thus retained in its elevated position, it would fall by gravity to a nearly closed position, and would become tangled with the parallel threads at the time the hook 12 is being entered between said threads on its 10 downward movement.

Another advantage lies in mounting the yieldable spring or resilient material in the space between the inner edge of the latch and the hook portion, without increasing the size 15 of the body portion of the needle.

I claim as my invention:

1. A knitting needle comprising a body portion having one end terminating in a hook, said body portion being provided with a central slot between its back and front edges and adjacent to the inner edge of said hook, a latch having one end pivoted in said slot and its free end designed to overlap the free end of said hook, yieldable means mounted entirely 20 within the inner end of said slot between the latch and said hook to be engaged by the inner edge of said latch when it is moved to a

nearly closed position for automatically throwing said latch to an open position, the forward edges of the upper end of the side 30 members of said slot being bent slightly inwardly and the body portion of said latch being adapted to frictionally engage the inwardly bent portions of said side members when moved to its open position. 35

2. A knitting needle comprising a body portion having one end terminating in a hook, said body portion being provided with a central slot between its back and front edges and adjacent to the inner edge of said hook, a latch having one end pivoted in said slot and its free end designed to overlap the free 40 end of said hook, yieldable means for automatically throwing said latch to an open position as the latch is moved to a position to close 45 said hook, the forward edges of the upper end of the side members of said slot being bent slightly inwardly and the body portion of said latch being adapted to frictionally engage the inwardly bent portions of said side 50 members when moved to its open position.

Des Moines, Iowa, April 16, 1927.

CARL E. B. OSBERG.
